UNITED STATES PATENT OFFICE.

WALKER GILL WYLIE, JR., OF RED BANK, NEW JERSEY.

SETTING FRAME.

Application filed April 28, 1926. Serial No. 105,081.

The present invention relates to setting frames and aims to provide certain improvements therein. More particularly, it concerns itself with the winding or setting of loom spools for use in the making of Axminster rugs or the like of any desired shape, either symmetrical or unsymmetrical, oval, circular, semi-circular, diamond-shaped, etc., or of a width narrower than the loom spools. A method for making such rugs is shown and described in my co-pending application Serial No. 99,485, filed April 3, 1926, which has eventuated in Patent No. 1,590,986, dated June 20, 1926, and consists in carrying out the weaving process in the usual way, but instead of the loom spools being wound or set with yarn to their full length from end to end, said spools are set with only the requisite number of threads necessary to provide the desired rug widths corresponding to the particular rows of tufts.

In winding or setting the yarn on the loom spools from the reel spools on the setting frame, the threads are first passed through the teeth of a comb or reed, the position of each tooth determining the position of a particular tuft of a row in the finished rug. In a 27 inch loom, for example, there are 189 tufts to a row, hence there are 190 teeth to the guiding comb or reed. Where the entire loom spool is to be wound or set, the enlarged ends of the spools serve as collars to prevent spreading of the terminal threads of yarn, but where the terminal

thread or threads are to be spaced from their respective ends of the spool, it is found that undue spreading will take place, which is augmented by the action of the compression rollers which are used to pack down the threads on the spool. This spreading of the terminal threads renders the drawing off of the thread ends through the proper openings in a tube frame very difficult, and materially interferes with the weaving process.

According to the present invention I provide a simple and efficient means of preventing undue spreading of the terminal threads without resorting to any material change in the setting frame or needlessly multiplying the loom spools so as to provide a separate

loom spool for every possible loom spool setting. This I accomplish by providing means between the reed and loom spool in close proximity to the latter, said means preferably consisting of a spool or roller provided with a pair of collars which are adjustable along the length of the spool, and co-operating means on the collars and spool for holding said parts in any adjusted position. I also prefer to provide said spool with a gauge or index which will aid the setter in accurately positioning the terminal threads in accordance with a master design. The invention also includes other features of novelty which will be hereinafter more fully described.

A preferred embodiment of my invention is shown in the accompanying drawings, wherein—

Figure 1 is a perspective view of a setting frame embodying my invention.

Fig. 2 is a transverse section taken on the plane of the line 2—2 of Fig. 1.

Fig. 3 is an elevation partly in section of a detail of the invention.

Fig. 4 is a section taken on the line 4—4 of Fig. 3.

Referring to the drawings, let A indicate the setting frame as a whole, having as its essential component parts a bank of reel spools B, a comb or reed C and a loom spool supporting frame D. The frame D may be of any approved construction and usually consists of a pair of standards or uprights E adapted to support a loom spool F, so that the latter may be freely rotated, and a set of compression rollers G, G¹ and G² so mounted on the frame E as to provide a substantially equally distributed compression action upon the yarn being wound on the loom spool. The specific arrangement or the manner in which this compression action is brought about does not constitute a part of this invention, and merely by way of illustration, the rollers G, G¹ and G² are shown as mounted on the ends of pivoted levers g, g¹ and g² so as to be urged into contact with the yarn on the loom spool by the action of gravity. These rollers, it will be seen, snugly fit between the collars on the

end of the loom spool F. The construction thus far described is the conventional setting frame used in winding or setting loom spools for use in weaving Axminster rugs, and is quite efficient for this purpose where the loom spools are to be set from end to end. However, where, in accordance with the method outlined in my aforesaid co-pending patent, many of the loom spools are to be wound or set with the terminal threads of yarn spaced from the ends of the loom spools, it will be appreciated that owing to the action of the compression rollers upon the threads being wound, that the terminal threads will be caused to unduly spread or run off from their true position. To overcome this deficiency, I have provided the setting frame with a supplemental spool or roller H positioned between the reed C and the loom spool to be wound, and preferably said supplemental spool is set as near as possible to the loom spool being wound.

The roller H may be mounted either upon the standards E or any other supporting means, and in its preferred construction consists of a spool substantially similar to a loom spool and has a pair of collars J adjustable to various positions along the length of the spool. The specific manner of carrying out the adjustability of the collars is immaterial, and I have herein shown these means as consisting of a strip K seating in a groove which extends the length of the spool H and being substantially flush therewith, said strip being provided with a plurality of openings k substantially in alignment and agreeing in number with the teeth on the comb or reed C, and the collars J each having a bushing portion j supporting an encircling spring L, the free end of which carries a detent device l passing through an opening in said bushing and engageable in the openings k. The free end l' of the spring may be formed to provide a finger manipulating portion whereby the detent may be raised from its locking position in an opening k and thereby permit the collar J to be moved to any other position along the spool H. To facilitate the setting of the terminal threads I provide the spool adjacent the strip K with gauge markings or an index M, which, at a glance, will aid the setter in positioning the collars J to agree with the position of the terminal threads on the master design to be set, in which positions the collars will serve to guide and prevent undue spreading of said terminal threads upon the loom spool being wound. It will be appreciated that the closer the proximity of the guide means to the loom spool being wound, the less will be the spreading or overrunning of the terminal threads thereon.

While I have shown and described the preferred embodiment of my invention, it is to be understood that I do not wish to be lim-

ited to the precise construction disclosed, since modification thereof may be resorted to without departing from the spirit of the invention.

What I claim is:

1. A setting frame comprising a reed through which the yarn threads are guided, a loom spool to be wound or set, and means to guide and prevent undue spreading of a terminal thread of yarn while winding the loom spool where such thread is to be wound in spaced relation to the end of the loom spool, said means comprising a guiding element adjustable to various positions along a line parallel to the axis of said loom spool in proximity thereto. 70

2. A setting frame comprising a loom spool to be wound or set, and means to guide and prevent undue spreading of a terminal thread of yarn while winding the loom spool where such thread is to be wound in spaced relation to the end of the loom spool, said means comprising a guiding member in close proximity to the loom spool. 85

3. A setting frame comprising a reed through which the yarn threads are guided, a loom spool to be wound or set, and means to guide and prevent undue spreading of a terminal thread of yarn while winding the loom spool where such thread is to be wound in spaced relation to the end of the loom spool, said means comprising a member in close proximity to the loom spool having a guiding element adjustable along the length of said member. 95 100

4. A setting frame comprising a reed through which the yarn threads are guided, a loom spool to be wound or set, and means to guide and prevent undue spreading of a terminal thread of yarn while winding the loom spool where such thread is to be wound in spaced relation to the end of the loom spool, said means comprising a member parallel to said loom spool disposed in advance thereof and in close proximity thereto, having a guiding element adjustable to various positions along the length thereof, and a gauge on said member to facilitate the position of said adjustable element. 110 115

5. A setting frame comprising means for supporting a loom spool, a reed or comb in advance of said supporting means, and a member intermediate said reed and said supporting means to guide and curtail the spreading of a terminal thread of yarn while winding a loom spool where such terminal thread is to be wound in spaced relation to the end of the loom spool. 120

6. A setting frame comprising means for supporting a loom spool and a member extending transversely across said frame in advance of said spool supporting means, said member having a plurality of openings therein, a yarn guiding element adjustable along said member to any yarn position on 130 125

a loom spool and means on said element engageable in the openings.

7. A setting frame comprising means for supporting a loom spool and a roller extending transversely across said frame in advance of said spool supporting means, said roller having a plurality of openings therein along a line parallel to its axis, a collar adjustable along said roller to any yarn position on a loom spool and a detent device on said collar engageable in said openings.

In witness whereof, I have hereunto signed my name.

WALKER GILL WYLIE, Jr.
